UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

PLUG RECEPTACLE.

Application filed January 24, 1923. Serial No. 614,544.

This invention relates to plug receptacles which are encased in a strong rigidly-supported, weather-proof conduit outlet box or housing, and has for its object a particularly simple construction, arrangement and assembly of the housing and the receptacle proper by which the receptacle proper is supported in a simple and efficient manner and is readily accessible, for removing it for repairs, and for initially installing it and connecting the wire terminals thereof to the service wires leading into the housing from the conduit enclosing the service wires.

The invention consists in the novel features and in the combinations and constructions hereinafter set forth and claimed.

In describing this invention, reference is had to the accompanying drawings, in which like characters designate corresponding parts in all the views.

Figure 1 is an elevation, partly broken away, of this plug receptacle.

Figure 2 is an inner end view of the outer section of the housing.

Figure 3 is a plan view of the receptacle proper and support therefor.

This plug receptacle comprises a two-part housing or conduit outlet box, the dividing line between the sections of which extend transversely of the housing, or box, the rear section enclosing a chamber for the inlet of the service wires and having means as a threaded nipple for connection to the conduit enclosing said wires, a receptacle proper comprising a body extending into the front section, a support for the body extending between the abutting ends of the sections, and means for holding the sections together.

1 designates the housing which is cylindrical in general form and open at its outer or front end, and closed at its inner or rear end, it being provided at its inner or rear end with an internally threaded nipple 2 for connection to a conduit enclosing the service wires. It is also formed at its rear end with laterally extending flanges 3 by which it may be rigidly secured to the support, as by screws, passing through holes 4 in said flanges.

5 and 6 are respectively the front and rear sections of the housing, the dividing line extending transversely of the cylindrical housing nearly midway between the ends of the same. The front section 5 is open at its outer or front end to permit the entrance of

a plug into the plug receptacle proper supported within the housing, and the rear section is closed at its inner or rear end enclosing a chamber 7 for the service wires.

8 is the body of the receptacle proper, said body being of insulating material. 9 are wire terminals on the rear end portion of the body for connection to the service wires in the chamber 7. 10 are plug terminals extending through passages 11 in the outer portion of the body, these being continuations of, or in line with the terminals 9 and being here shown as tubular, to receiving the projecting plug terminals of a plug designed to coact with this plug receptacle.

12 is the support for the body 8, said support extending between the abutting faces of the sections 5, 6, and also having a portion engaging the inner face of the housing for centering the body 8.

As here illustrated, the support is attached to the body between the ends of the body so that the rear portion 13 of the body carrying the wire terminals 9 extends into the rear section 6 and such rear portion 13 is of less diameter than the major part of the body 8 leaving a face or ledge 14 around the portion 13, and the support 12 has lugs 15 seated in depressions in said ledge and secured to the body as by rivets 16. Said support is also shown as formed with laterally extending diametrically opposite flanges or lugs 17 seated in depression 18 in the rear edge face of the front section 5. The lugs 17 are of different size or form and likewise the depressions 18 are of corresponding forms, as the lugs they receive, so that the support 12 with attached body 8 can be placed in the housing in one position only.

The support 12 is also formed with an arc-shaped portion 19 for fitting the interior wall of one side only of the section 5; and a spring 20 is interposed between the opposite side of the receptacle and the body 8 and holds the support centered. This spring 20 is a tongue attached to the section 5, the free end of the tongue bearing against the body 8.

The means for holding the sections together are usually screws 21 extending through ears 22, 23, on the sections 5, 6, near the abutting edges of the sections, each screw passing freely through a hole in one ear and threading into the other ear.

The ears 22, 23, are preferably located

adjacent the depressions 18 in which lugs 17 of the support 12 are seated.

Owing to the arrangement of the sections of the housing and the support for the body 5 of the receptacle, the drawing of the service wires from the conduit into the box, the connection of the wires to the terminals of the plug receptacle body, and the final securing of the receptacle in the housing is 10 easily and quickly accomplished.

What I claim is:

1. In a plug receptacle; a two part housing, said parts including tubular sections arranged end to end, the rear section having 15 means for connection to an electrical conduit, a plug receptacle proper comprising a body extending into the front section, a support for the body extending between the abutting ends of the tubular section, means 20 for holding the sections together, the support having end portions extending between the sections and a portion between its ends engaging one side of the interior wall of the tubular housing, and a spring interposed 25 between the body and the housing, and acting on the plug receptacle body to thrust

said portion of the support against the interior wall of said housing.

2. In a plug receptacle, a two part housing, said parts including front and rear sections arranged end to end, the rear section having means for connection to an electric conduit, a plug receptacle proper comprising a body extending into the front section and spaced apart from the inner wall of the 35 housing, a support for the body having lugs at its ends extending between the abutting ends of the tubular sections, the lugs being of different size and one of the abutting end faces of the sections having complementary 40 recesses for receiving the lugs, the support being flat and the body of the receptacle extending above and below the same, the support having an intermediate portion between the lugs for engaging the inner wall of the 45 housing and means for holding the sections together.

In testimony whereof, I have hereunto signed my name, at Syracuse, in the county of Onondaga, and State of New York, this 18th day of Jan., 1923.

CARL H. BISSELL.
